UNITED STATES PATENT OFFICE.

BLANCHE A. MACARTHUR, OF LOS ANGELES, CALIFORNIA, ASSIGNOR TO EARLE C. ANTHONY, INC., OF LOS ANGELES, CALIFORNIA, A CORPORATION OF CALIFORNIA.

DESIGN FOR A STEP PLATE.

Application filed April 28, 1924. Serial No. 9,423. Term of patent 14 years.

To all whom it may concern:

Be it known that I, BLANCHE A. MACARTHUR, a citizen of the United States, residing at Los Angeles, in the county of Los Angeles and State of California, have invented a new, original, and ornamental Design for Step Plate, of which the following is a specification, reference being had to the accompanying drawings, forming part thereof.

In the drawings:

Figure 1 is a top plan of a step plate showing my new design.

Figure 2 is a front elevation of the step plate shown in Figure 1; and

Figure 3 is an end elevation of the step plate shown in Figure 1.

I claim:

The ornamental design for a step plate, as shown.

Signed at Los Angeles, California, this 19th day of April, 1924.
